UNITED STATES PATENT OFFICE.

WILLIAM A. HARTLINE, OF PENNS GROVE, NEW JERSEY.

DESIGN FOR A SERVICE-PIN.

53,501.

Specification for Design.

Patented July 8, 1919.

Application filed March 4, 1919. Serial No. 280,680. Term of patent 3½ years.

To all whom it may concern:

Be it known that I, WILLIAM A. HARTLINE, a citizen of the United States, residing at Penns Grove, in the county of Salem and State of New Jersey, have invented a new, original, and ornamental Design for a Service-Pin, of which the following is a specification, reference being had to the accompanying drawing, forming part thereof.

The figure is a front elevational view of a service pin showing my new design.

I claim:—

The ornamental design for a service pin as shown.

WILLIAM A. HARTLINE.

Witnesses:

S. P. COLE,

DAVID P. FEATHERN.
